PROCESS FOR PRODUCING DE-WAXED
CITRUS OILS

Horton E. Swisher, Upland, Calif., assignor to Sunkist Growers, Inc., Los Angeles, Calif., a corporation of California
No Drawing. Filed Apr. 3, 1961, Ser. No. 100,016
14 Claims. (Cl. 260—236.6)

This invention relates to the treatment of citrus products and has particular reference to a process for the production of de-waxed citrus oils and other essential oils.

Wax-free citrus oil, particularly cold pressed lemon oil, is in great demand, the purchasers of lemon oil requiring that it meet with U.S.P. requirements, one requirement being that the oil shall produce a clear alcoholic extract. In recent years the problem of removal of wax and wax-like materials from citrus oils has become increasingly difficult and it has become virtually impossible to produce U.S.P. lemon oil, due in part at least to the changes that have taken place in the waxing of citrus fruits. Because of the need for fruit-waxing compositions that have high gloss and effectively prevent shrinkage of the fruit on storage, new and better wax compositions are constantly being formulated. Among the materials that are being introduced into these wax compositions are carnauba wax, paraffin wax, limed polypale resin, polymerized terpenes and coumarone-indene resins.

Some of these newer wax additives, such as coumarone-indene resin, are so highly soluble in citrus oils and so chemically unreactive that heretofore there has been no known way to remove them without altering the composition of the oil. Naturally occurring waxes or stearoptenes can be effectively removed by low temperature filtration of the oil using means known in the art, but such materials

Still another object of the present invention is to provide an improved process for the extraction of a substantially wax-free oil from the peel of citrus fruit. Other objects and advantages of the present invention it is believed will be readily apparent from the following detailed description of preferred embodiments thereof. Briefly, this invention comprehends within its scope the discovery that synthetic and natural waxes and wax-like materials present in essential oils such as citrus oils are precipitated by the addition to the oil of an oil-soluble fluorochlorohydrocarbon. Such compounds have been found to be ideally suited as de-waxing solvents for such difficultly removed compounds as coumarone-indene resin and in addition, these de-solvents also easily remove other wax additives as well as the naturally occurring stearoptenes of the citrus oils. Further, it has been found possible to control the amount of wax removal by regulating the quantity of de-solvent. It has further been discovered that in addition to utilizing these compounds as by addition to the pressed oil, the compounds can be used to extract the oil from the peel and simultaneously bring about the separation of the wax from the oil.

The process of the present invention is particularly adapted to the de-waxing of such citrus oils as lemon, lime, orange, grapefruit and tangerine, but other terpene-containing essential oil, such as those of the mint group can also be treated in accordance with the present invention.

The fluorochloromethanes and ethanes have been found to be particularly suitable for use in the process of the present invention. A list of compounds useful within the scope of the present invention is set forth in Table I.

TABLE I
Physical Properties of Fluorocarbon Compounds

Chemical name	Formula	B.P. at 1 atm., °C.	Density of liquid at 30° C.	Heat of vaporization at B.P., B.t.u./lb.	Specific heat of liquid at 30° C., B.t.u./lb./°F.	Viscosity of liquid at 30° C., centipoise

as coumarone-indene resin have sufficient solubility in lemon oil to remain in solution even when the oil is chilled and filtered at -78° C. Since citrus fruits that are received by the oil processing plants are largely those that have been waxed in the packing house, they contain varying amounts of both the naturally occurring and synthetic waxes. In pressing the citrus oil from the peel, it is virtually impossible to prevent contact of the oil and surface wax and as a consequence, a considerable amount of the natural and added surface wax becomes dissolved in the oil during the pressing operation.

A primary object of the present invention is therefore to provide a process for the removal of synthetic and natural waxes and wax-like material from citrus oils and other essential oils.

A further object of the present invention is to provide a process for the production of lemon oil meeting the requirements of the U.S.P.

All of the straight chain fluorochlorohydrocarbons listed in Table I are miscible with citrus oils. The cyclic compound, octafluorocyclobutane, however, has been found to be immiscible with the oils. It is useful as a de-solvent in the process of the present invention only when it is used in combination with the other compounds in amounts low enough to be miscible with these oils. In addition to the wholly chlorofluorinated hydrocarbons set forth, partially fluorinated hydrocarbons that are oil-miscible such as dichloromonofluoromethane and monochlorodifluoromethane can be used, either alone or in combination with the wholly chlorofluorinated hydrocarbons, which of course can also be used in mixtures of two or more.

In carrying out the process of the present invention, as applied to the de-waxing of an extracted oil, the de-solvent is simply mixed, in the liquid state, with the oil and the mixture allowed to stand for a sufficient length of time to

precipitate the wax. The wax is removed from the oil and de-solvent mixture by any convenient method such as filtration, and the oil is recovered by vaporizing the de-solvent therefrom.

An alternate method comprises the use of the de-solvent as an extractive solvent for the peel oil. That is, the de-solvent is mixed, for example, with citrus peel flavedo, the de-solvent preferentially dissolving or extracting the citrus oil without bringing the wax into solution. The de-solvent is removed from the oil in the same manner as above, 10 to produce the de-waxed citrus oil product.

The following specific examples are illustrative of the process of the present invention, but it is to be understood that the invention is not to be limited to the specific details thereof.

For purposes of determining whether the citrus oils produce clear alcoholic extracts the standard test applied in each case was as follows: 1 cubic centimeter (cc.) of the citrus oil was mixed at room temperature in a stoppered test tube with 9 cc. of 95% ethyl alcohol and the mixture observed for formation of cloud. After 24 hours the mixture was again observed for any precipitate that might have formed.

EXAMPLE 1

For this test a commercial sample of clarified cold pressed lemon oil which had been unsuccessfully de-waxed by a standard treatment at -40°C . was used. As is indicated in Table II below, several ratios of de-solvents were used with this lemon oil to establish the proper amounts required to effect sufficient de-waxing so as to produce cloud-free alcoholic extracts. The oil and the dichlorotetrafluoroethane were mixed at -10°C . in a Fischer and Porter glass vessel, allowed to stand 15 minutes at -10°C . and the precipitated wax removed from the lemon oil 20 de-solvent mixtures at atmospheric pressure by gravity filtration through paper.

Because of the lower boiling points of the dichlorodifluoromethane and monochlorodifluoromethane they were mixed and filtered at -30°C . and -40°C . respectively.

The lemon oil was recovered by heating the mixture on a steam bath sufficiently to vaporize the low-boiling de-solvent. The lemon oil thus obtained was tested for cloud in alcoholic solutions as detailed above, with the results indicated in Table II.

top of the glass vessel within 5 minutes to form a heavy flocculant precipitate which occupied 6.8% of the total volume of the mixture. The mixture was filtered rapidly at 0°C . through paper and the de-solvent separated from the oil by heating to 50°C . under a partial vacuum.

The de-waxed oil prepared in the above manner gave a sparkling alcoholic extract whereas the untreated oil contained a large amount of flocculant precipitate. When both the treated and untreated oils were examined by methods of gas phase chromatography at temperatures of 65°C ., 100°C . and 150°C ., no discernible differences in either composition or traces of residual solvent were noted. The de-waxed oil had a normal evaporation residue of 2.32%.

EXAMPLE 3

One volume of the same cold pressed lemon oil as used in Example 2 above was mixed with 3 volumes dichlorotetrafluoroethane at 0°C . in a Fischer and Porter glass aerosol pressure bottle whereupon a wax precipitate formed. The mixture was shaken periodically while being allowed to warm up slowly through the temperature range from 0°C . to 25°C . At temperature intervals of 5°C ., samples of oil and de-solvent mixture were withdrawn immediately after vigorous shaking, through an aerosol spray nozzle. The fine spray of the nozzle was directed into a paper filter where the sudden expansion to atmospheric pressure of the mixture caused a temperature drop below the boiling point of dichlorotetrafluoroethane. The de-waxed lemon oil that passed through the filter paper was warmed to remove the residual desolvent and made up into alcoholic extracts. All of the oils, which were withdrawn at temperatures of 10°C ., 15°C ., 20°C . and 25°C ., gave clear alcoholic extracts. By way of comparison, another mixture was made up in the same manner in a glass pressure bottle, but in this case the mixture was withdrawn at 25°C . from the clear liquid below the top wax layer and was not filtered after being released to atmospheric pressure. After removing the residual desolvent, this oil produced a very slight haze in the alcoholic extract made therefrom. The untreated control lemon oil produced a large amount of flocculant precipitate in alcohol.

Thus, it can be seen that the waxes of the lemon oil have a slight solubility in the mixture of oil and de-solvent at 25°C . However, the wax can be effectively removed

TABLE II

De-waxing Clarified Cold Pressed Lemon Oil

Test No.	Parts Lemon oil (by vol.)	De-waxing treatment			Alcoholic Extract	
		De-solvent	Parts de-solvent (by vol.)	Appearance of cloud in mixture	After 15 min.	After 24 hours
1.....	Control				Slight cloud	Moderate precipitate.
2.....	2 Dichlorotetra- fluoroethane.	1	Remained clear		do	Do.
3.....	1 do	1	Slightly hazy		do	Do.
4.....	1 do	2	Small flocculant precipitate.		Very slight cloud.	Slight precipitate.
5.....	1 do	2.5	Flocculant pre- cipitate.		Clear	No precipitate.
6.....	1 do	3	do		do	Do.
7.....	1 Dichlorodi- fluoromethane.	2.5	Small flocculant precipitate.		Very slight cloud.	Very slight precipitate.
8.....	1 do	3	Flocculant precip- itate.		Clear	No precipitate.
9.....	1 Monochlorodi- fluoromethane.	3	Small flocculant precipitate.		Very slight cloud.	Very slight precipitate.

EXAMPLE 2

One volume of a commercial sample of cold pressed lemon oil, which had been only partially de-waxed in manufacture, was mixed with 3 volumes dichlorotetrafluoroethane at 0°C . in a glass pressure vessel. A dense cloud of wax formed almost immediately and rose to the 70

from the lemon oil even at ambient temperatures by allowing the de-solvent to provide its own evaporative cooling by expansion, just prior to filtration or centrifugation.

EXAMPLE 4

The de-waxing method described above was repeated with cold pressed grapefruit oil, cold pressed orange oil

and concentrated (5-fold) orange oil. One volume of each oil was mixed with 3 volumes dichlorotetrafluoroethane at 0° C. in a pyrex glass bottle, allowed to stand 30 minutes, filtered cold through paper and the de-solvent evaporated. Considerable wax separated from each of the oils. When mixed with alcohol as previously described, the grapefruit oil gave a clear extract whereas the control was cloudy. In the case of the cold pressed and concentrated orange oil, the cloud was improved over the controls, but complete clarity was not achieved. It should be pointed out that the U.S.P. specification for cold pressed orange oil requires only that it be miscible with dehydrated alcohol, a test that is less severe than the test applied in this case.

EXAMPLE 5

In another experiment, 3000 p.p.m. of coumaroneindene resin was added to one sample of clarified lemon oil, 1000 p.p.m. of limed polypale resin added to another and 1% (by weight) of the soft wax separated from lemon oil in the plant centrifuges added to other. In each case the lemon oil resulting from treatment with 3 volumes of dichlorotetrafluoroethane gave clear alcoholic extract.

In commercially applying this process for de-waxing citrus oils, the de-solvent treatment of the oil is preferably accomplished in a closed system by mixing, removing the coagulated waxes by filtering, centrifuging, etc. After wax removal the de-solvent is separated from the oil in an evaporator and the oil drawn off. After condensing the de-solvent it is ready for recycling in continued use.

The final traces of de-solvent in the oil may be removed by vacuum treatment and/or warming as required. Alternatively, purging with nitrogen gas also may be used. If desired the oil may be washed with water to remove any water-soluble or water-miscible trace components.

The amount of de-solvent required varies, depending upon the type of de-solvent, the type of oil being de-waxed and the wax content thereof. Generally speaking, this ranges from about 1 to 5 volumes of de-solvent for each volume of oil, with from about 2 to about 4 volumes of de-solvent per volume of oil being preferred.

Whereas all the above examples have covered de-waxing citrus oils that were made by the usual process in which the unwanted waxes were already present in the cold pressed oils, the following example circumvents this problem by using the de-solvent as an extractive solvent for the peel flavedo. Thus, it is possible to make a lemon oil producing cloud-free alcoholic extracts simply by extracting the peel with a solvent that preferentially dissolves the citrus oil without bringing the wax into solution.

EXAMPLE 6

24 grams of finely grated lemon peel were chilled and mixed with 60 cc. of dichlorotetrafluoroethane at 0° C. in a glass pressure vessel. The mixture was allowed to warm up to room temperature, with occasional shaking, over a period of 3 hours. Following this treatment the mixture was again chilled to 0° C. and filtered through paper to separate the peel and desolvent-oil mixture. After removing the de-solvent by warming on a steam bath, the recovered lemon oil was tested for cloud by preparing an alcoholic extract. This extract was sparkling clear.

As will be apparent to those skilled in the art from the above examples, the present method for the removal of waxy constituents from essential oils has certain definite advantages, as follows:

- (1) It generally requires only from two to three volumes of de-solvent for each volume oil to be de-waxed, which is a favorable ratio by comparison with other methods.
- (2) It does not require extremely low temperatures for efficient removal of wax.
- (3) Rather than the typical soft slimy wax formed when stearoptenes are formed at low temperatures in oil, the wax that separates in the mixtures of oil and de-solvent

tends to be hard and easily removed by filtration or by centrifugation.

- (4) The viscosity of the oil and de-solvent mixture is low, even at very low temperatures, making filtration easy.
- (5) Because of the resulting high density of the oil and de-solvent mixture, the lighter wax tends to float to the surface, thus facilitating removal.
- (6) The low boiling points of the de-solvent compounds makes possible their removal from the oil without having to subject the mixture to relatively high temperatures.
- (7) The heat of vaporization of the de-solvents is only a fraction of that of other possible de-solvents. Thus, much less heat energy is required to remove the de-solvents of the present invention from the oil than would be required for other known de-solvents.

Having fully described my invention, it is to be understood that I do not wish to be limited to the details set forth, but my invention is of the full scope of the appended claims.

I claim:

1. A process for removing coumarone-indene resin from citrus oil comprising the steps of subjecting a citrus oil which contains coumarone-indene resin to the action of a sufficient volume of a citrus oil-soluble fluorochlorohydrocarbon is selected from the group consisting of trichloromonofluoromethane, dichlorodifluoromethane, dichloromonofluoromethane, monochlorodifluoromethane, trichlorotrifluoroethane, dichlorotetrafluoroethane, and mixtures thereof to precipitate the resin, separating the precipitated resin from the liquid phase and separating the fluorochlorohydrocarbon from the citrus oil.
2. The process of claim 1, wherein the fluorochlorohydrocarbon is used in an amount between about one and about five volumes for each volume of oil.
3. The process of claim 1 wherein the fluorochlorohydrocarbon is mixed with the oil, wherein the wax precipitate is filtered from the liquid phase, and wherein the fluorochlorohydrocarbon is separated from the oil by heating the liquid phase to vaporize the fluorochlorohydrocarbon.
4. The process of claim 3 wherein the fluorochlorohydrocarbon comprises from about two to about four volumes of dichlorotetrafluoroethane for each volume of oil.
5. The process of claim 3 wherein the fluorochlorohydrocarbon comprises from about two to about four volumes of dichlorodifluoromethane for each volume of oil.
6. The process of claim 3 wherein the fluorochlorohydrocarbon comprises from about two to about four volumes of monochlorodifluoromethane for each volume of oil.
7. The process of claim 1 wherein the fluorochlorohydrocarbon is added to citrus peel to extract the substantially wax-free oil therefrom.
8. The process of claim 1 including the steps of adding the fluorochlorohydrocarbon to the oil-bearing portions of the citrus peel at a temperature below the boiling point of the fluorochlorohydrocarbon, warming the admixture to room temperature, chilling the admixture to a temperature below the boiling point of said fluorochlorohydrocarbon, separating the liquids from the solids, and heating the liquids to vaporize the fluorochlorohydrocarbon therefrom.
9. The process of claim 8 wherein the fluorochlorohydrocarbon comprises from about two to about four volumes of dichlorodifluoromethane for each volume of oil.
10. The process of claim 8 wherein the fluorochlorohydrocarbon comprises from about two to about four volumes of dichlorotetrafluoroethane for each volume of oil.

11. The process of claim 8 wherein the fluorochloro-hydrocarbon comprises from about two to about four volumes of monochlorodifluoromethane for each volume of oil.

12. The process of claim 4 wherein the citrus oil is 5 lemon oil.

13. The process of claim 1 wherein said citrus oil comprises a cold pressed citrus oil.

14. The process of claim 1 wherein said oil comprises a cold pressed lemon oil and said fluorochlorohydro-carbon comprises dichlorotetrafluoroethane.
